UNITED STATES PATENT OFFICE.

WILLIAM G. CUMMINS, OF McMINTVILLE, TENNESSEE.

HORSE-DETACHER.

SPECIFICATION forming part of Letters Patent No. 227,740, dated May 18, 1880:

Application filed September 25, 1879.

To all whom it may concern:

Be it known that I, WILLIAM G. CUMMINS, of McMintville, in the county of Warren and State of Tennessee, have invented certain new and useful Improvements in Horse-Detachers; and I do hereby declare the following to be a full, clear, and exact description of the invention, such as will enable others skilled in the art to which it pertains to make and use it, reference being had to the accompanying drawings, which form part of this specification.

My invention consists, first, in the combination, with a whiffletree having ferruled ends and bearings having right-angular shanks fastened in the latter, of a rotary detaching-shaft journaled in perforations formed in said bearings and guards pivoted to the outer ends of the bearings; second, in the combination, with bearings having right-angular shanks which enter the whiffletree ends, of a rotary detaching-shaft journaled therein and spring-guards pivoted to the outer ends of said bearings, the latter having their inner faces recessed to receive said guards.

Referring to the drawings, Figure 1 is a perspective view. Fig. 2 is a central transverse section. Fig. 3 is a perspective view, showing the device unfastened.

The whiffletree A has its central portion provided with a catch, a, and its extremities provided with rearwardly-inclined bearings B. The latter have angular shanks b, which enter the ferruled ends c of the whiffletree. The rotary detacher C is made in continuous straight form, and has its central portion provided with a single arm, D, whose free end detachably engages with catch a. Any suitable connection, E, is secured to said free end of the arm and extends to the vehicle.

The rearwardly-curved ends d of the rotary detacher are journaled in holes formed in bearings B, and the latter have their free extremities provided with the trace-guards F, respectively pivoted thereto. The inner face of each of said bearings is provided with a recess, e, within which the corresponding guard fits, said guards being adapted to be sprung into and out of said recess and swung up or down in a vertical plane, in order to lock and

unlock the traces relative to the detacher ends d. 50 A bifurcated wire and plate hinge, G, secured to the central portion of the whiffletree, embraces the rotary detacher respectively on both sides of its arm. It prevents longitudinal movement of the rotary detacher, and also provides 55 a bearing for the arm to strike against as the latter is drawn backward, thereby determining the rotary movement of the detacher C.

The parts are constructed so as to spring the central portion of the rotary detacher out 60 from the whiffletree, thereby causing the rotary detacher to be automatically held in position to secure the traces thereto by its own lateral spring-pressure.

The operation of the device is evident. The 65 spring-guards are thrown out from their recesses and upward in vertical line, in order to connect or disconnect the traces with the rotary detacher, and by pulling the connecting device, which leads from the detacher-arm to 70 the vehicle, the rotary detacher is operated so as to cause the traces to automatically disengage themselves therewith.

Having fully described my invention, what I claim as new, and desire to secure by Letters Patent, is—

1. The combination, with the ferruled whiffletree ends and the bearings having right-angular shanks fastened therein, of the rotary detacher journaled in perforations formed in 80 said bearings and the guards pivoted to the outer ends of the bearings, substantially as set forth.

2. The combination, with the bearings having right-angular shanks which enter the 85 whiffletree ends, of the rotary detacher journaled therein and the spring-guards pivoted to the outer ends of said bearings, the latter having their inner faces recessed to receive said guards, substantially as set forth. 90

In testimony that I claim the foregoing I have hereunto set my hand this 22d day of September, 1879.

WILLIAM G. CUMMINS.
